UNITED STATES PATENT OFFICE.

EMMA BERNER MEHLEM, OF CHICAGO, ILLINOIS.

CROCHET PATTERN.

Application filed September 22, 1924. Serial No. 739,221.

To all whom it may concern:

Be it known that I, EMMA BERNER MEHLEM, a citizen of the United States, residing at Chicago, in the county of Cook and State of Illinois, have invented certain new and useful Improvements in Crochet Patterns; and I do declare the following to be a full, clear, and exact description of the invention, such as will enable others skilled 10 in the art to which it appertains to make and use the same.

My invention aims to provide a simple and desirable pattern by means of which numerous articles may be crocheted in an 15 orderly fashion, without the necessity of continually counting stitches, the device being particularly well adapted for the crocheting of sweaters, vests, and similar ladies' apparel, most of which are provided 20 with artistic designs to be crocheted in colors distinguishing from the main body of the article.

With the foregoing in view, the invention resides in the novel subject matter herein- 25 after described and claimed, the description being supplemented by the accompanying drawing.

Figure 1 is a side elevation of a pattern embodying my invention. 30 Figure 2 is a similar view showing the work partly completed over the pattern.

Figure 3 is a detail section on line 3—3 of Fig. 2.

In the drawing above briefly described, 35 the numeral 1 designates a backing sheet which is preferably formed of textile fabric, said sheet being cut to the desired shape of the article or section of an article to be crocheted, one section of a vest being the 40 shape of the backing sheet herein disclosed. The sheet 1 is provided with a plurality of parallel horizontal lines 2 having individual identifications at opposite ends, such as the numbers shown. These guide lines are effec- 45 tive to cause the person using the pattern to make her rows of crocheting in a straight orderly manner, which is insured by finishing any row on the same line upon which it was started.

50 Rows of basting stitches 3 are engaged

with the backing sheet 1 and extend across the guide lines 2, and at intervals, the rows of crocheting are engaged with these basting rows so that the work is held down flatly against said sheet, this being particu- 55 larly advantageous when the sheet is provided with a design which must be followed in a color or colors distinguishing from the main body of the work. In the preferred form of the invention, parallel vertical lines 60 4 are formed on the sheet 1, these lines and the lines 2 serving to divide said sheet into a plurality of blocks. Coloring matter 5 is applied to some of these blocks to produce any desired design or designs, and when 65 crocheting over any colored block, crochet cotton or wool of the same color is used. Thus, by producing the design or designs of the proper color or colors on the pattern and following such color or colors when 70 crocheting the work, said design will be duplicated on the latter, and it will be seen that in so doing, it is not necessary to continually count stitches as is now commonly done.

After completion of the work, the basting 75 threads 3 are cut and removed so that the backing sheet may be detached from the completed work, leaving the latter in a symmetrical condition.

As excellent results have been obtained 80 from the details disclosed, they may well be followed, but within the scope of the invention as claimed, modifications may of course be made.

I claim:

1. A crochet pattern comprising a back- 85 ing sheet, parallel guide lines thereon, and rows of basting stitches engaged with said sheet and extending across said guide lines for the purpose set forth.

2. A crochet pattern comprising a back- 90 ing sheet, parallel guide lines thereon, having individual identifications, and rows of basting stitches engaged with said sheet and extending across said guide lines for the purpose set forth.

3. A crochet pattern comprising a back- 95 ing sheet divided by horizontal and vertical lines into blocks, coloring matter filling some of said blocks, and forming one or 100

more designs, and rows of basting stitches engaged with said sheet for the purpose set forth.

4. A crochet pattern comprising a backing sheet divided by horizontal and vertical lines into blocks, coloring matter filling some of said blocks, and forming one or more de-

signs, individual identifications for the horizontal lines, and vertical rows of basting stitches engaged with said sheet for the purpose set forth. 10

In testimony whereof I have hereunto affixed my signature.

EMMA BERNER MEHLEM.
